W. P. SELLERS,
WINDOW PROVISION RECEPTACLE,
APPLICATION FILED MAR. 29, 1909.

Patented Apr. 5, 1910.

2 SHEETS—SHEET 2.

UNITED STATES PATENT OFFICE.

WILLIAM P. SELLERS, OF BATTLE CREEK, MICHIGAN.

WINDOW PROVISION-RECEPTACLE.

953,803.

Specification of Letters Patent. Patented Apr. 5, 1910.

Application filed March 29, 1909. Serial No. 486,518.

To all whom it may concern:

Be it known that I, WILLIAM P. SELLERS, a citizen of the United States, residing at the city of Battle Creek, Calhoun county, State of Michigan, have invented certain new and useful Improvements in Window Provision-Receptacles, of which the following is a specification.

This invention relates to improvements in provision chambers or receptacles.

My improved provision chamber or receptacle is particularly designed for attachment to a window although certain features are desirable for use in other relations.

The main objects of this invention are: First, to provide an improved provision chamber or receptacle adapted to be attached to a window which has adjustable securing means so that it may be fitted to windows of different widths. Second, to provide an improved structure of the class described in which the articles placed therein are conveniently accessible. Third, to provide a structure of the class described which is simple in structure, has effective ventilation, and, at the same time the articles placed therein are effectively protected.

Further objects, and objects relating to structural details, will definitely appear from the detailed description to follow.

I accomplish the objects of my invention by the devices and means described in the following specification.

The invention is clearly defined and pointed out in the claims.

A structure embodying the features of my invention is clearly illustrated in the accompanying drawing, forming a part of this specification, in which:

Figure 1 is a perspective view of my improved provision chamber or receptacle, it being shown attached to a window, parts of a window casing being illustrated in conventional form. Fig. 2 is a front perspective thereof removed from the window. Fig. 3 is a vertical section, taken on a line corresponding to line 3—3 of Fig. 1. Fig. 4 is a horizontal section, taken on a line corresponding to line 4—4 of Fig. 3. Fig. 5 is a vertical longitudinal section, taken on a line corresponding to line 5—5 of Fig. 3. Fig. 6 is a transverse section, taken on a line corresponding to line 6—6 of Fig. 5, the section being through the compartment which is accessible from the outside of the window.

Fig. 7 is an inverted plan of the roof of the casing, the same being taken on a line corresponding to line 7—7 of Fig. 6. Fig. 8 is an enlarged perspective showing the means for securing one of the window stop-engaging members 4. Fig. 9 is an enlarged vertical section, showing the securing means for one of the window stop-engaging members 4. Fig. 10 is a detail perspective of one of the filler members for filling in the space between the ends of the provision chamber or casing and the window casing.

In the drawing, similar reference characters refer to similar parts throughout the several views, and the sectional views are taken looking in the direction of the little arrows at the ends of the section lines.

Referring to the drawing, the casing or provision chamber is adapted to rest on a window-sill, as 2, and is secured in position by means of the stop-engaging members 3 and 4. The stop-engaging members 3 are adapted to telescope into the casing and are provided with longitudinal slots 5 through which the bolts 6 are arranged, the bolts being provided with nuts 7 for securing the stop-engaging members adjustably in position. The nuts 7 are preferably arranged on the inside of the casing, as appears in Fig. 8. The members 3 are preferably inclined outwardly so that water falling thereon will run outwardly instead of running into the casing. The members 3 are also preferably provided with brads 34 to engage the window casing. The stop-engaging members 4 are provided with longitudinal slots 8 through which the screws 9 are arranged, see Figs. 2 and 9, the stop-engaging members being preferably in the form of metal strips and being arranged on the front edge of the bottom 10 of the casing. The members 3 and 4 are adapted to engage the outer window stops 11, see Figs. 1 and 4. This effectively secures the provision casing to the window, and the nuts 7 being arranged on the inside of the casing, can be adjusted only from the inside. The bottom is preferably provided with rests 35 to which the brads 34 are secured.

The door 12 is pivoted at its upper edge so as to swing outwardly in opening, it being held in its closed position by the window when the window is closed,—that is, it is impossible to open the door when the window is down, as the bottom window closes.

down in front of the door. The upper end of the door is preferably arranged on the inside of the filler strip 13 of the casing, so that any water dripping down will run down on the outside of the door rather than drip into the casing.

10 The hinge for the door preferably consists of the loop-like strap 14 which engages the pivots 15 by allowing the door to be swung up and slid horizontally into the casing. Stops, as 16, are provided for the bottom of the door.

15 The casing is preferably provided with suitable shelves, as 17. I also preferably provide adjustable fillers to fill in the space between the ends of the provision chamber or casing and the window casing. These are preferably made up of telescoping sections 18 and 19, the top and bottom edges 20 of the section 19 being folded over the edges of the section 18, so that they are slidably connected. The outer ends of sections 18 and 19 are preferably flanged, as at 21 and 22, respectively, the flange 21 being provided with key-hole slots 23 adapted to engage the screws 24 on the ends of the provision chamber. The flange 22 is adapted to fit between the window stops 11, as clearly appears in Fig. 4. This filler is arranged between the stop-engaging members 3 and 4. When these fillers are employed, the window can be raised to the top of the casing to permit the opening of the door without admitting the outside air to the room.

30 35 I preferably provide the casing with a partition 25, which is arranged transversely to divide the chamber into compartments, one of the compartments being provided with a door, as 26, so that articles can be placed in the receptacle from the outside. This is a great convenience, as it allows a deliveryman to place articles into the provision receptacle and the same are also accessible from the inside.

40 45 The roof or top is preferably made up of an inner wall 27 and an outer wall 28, the outer wall being formed of sheet metal and having downturned flanges 29 at its edges to embrace the edges of the inner wall, the inner wall being provided with ventilating openings 30 at its upper and lower edges,—see Fig. 7. The inner wall is provided with ventilating openings 31, while the bottom is provided with a ventilating opening 32. 50 55 The openings 31 and 32 are covered with screens, as 33. This affords effective ventilation, and also secures a circulation through the roof, which assists in keeping the chamber cool.

60 65 My improved provision chamber or receptacle is readily attached and secured in place, and is very convenient in use. It is effectively ventilated so that, where desired, articles can be placed therein to cool, as any steam, odors or the like, readily escape, the

arrangement of the top and the ventilating openings thereof securing an effective draft.

Having thus described my invention, what I claim as new and desire to secure by Letters Patent, is:

70 75 80 85 90 95 100 105 110 115 120 125 130 1. The combination with a casing adapted to rest on a window-sill, of window stop-engaging members having longitudinal slots therein, the upper members being adapted to telescope into said casing, and the lower members being arranged on the front side of said casing at the bottom thereof; bolts for securing said upper stop-engaging members in position, arranged through the said slots thereof, said bolts being provided with nuts on the inside of said casing; screws for securing said lower stop-engaging members in position, arranged through the said slots thereof; fillers arranged at the ends of said casing between said stop-engaging members, said fillers being formed of sections, the top and bottom edges of one section being folded over the other whereby they are adjustably connected, the outer ends of said sections having flanges thereon, the flange of one section having key-hole slots therein to engage screws on the end of the casing, and the flange of the other being adapted to engage the stops of the window; a partition for said casing arranged transversely thereof; a door for the front of said casing, said door being hinged at its upper edge; and an outer door for said casing opening into one of the compartments thereof.

2. The combination with a casing adapted to rest on a window-sill, of window stop-engaging members having longitudinal slots therein, the upper members being adapted to telescope into said casing, and the lower members arranged on the front side of said casing at the bottom thereof; bolts for securing said upper stop engaging members in position, arranged through the said slots thereof, said bolts being provided with nuts on the inside of said casing; screws for securing said lower stop-engaging members in position, arranged through the said slots thereof; a partition for said casing arranged transversely thereof; a door for the front of said casing, said door being hinged at its upper edge; and an outer door for said casing opening into one of the compartments thereof.

3. The combination with a casing adapted to rest on a window-sill, of window stop-engaging members having longitudinal slots therein, the upper members being adapted to telescope into said casing, and the lower members arranged on the front side of said casing at the bottom thereof; bolts for securing said upper stop-engaging members in position, arranged through the said slots thereof, said bolts being provided with nuts on the inside of said casing; screws for securing said lower stop-engaging members in

- position, arranged through the said slots thereof; and fillers arranged at the ends of said casing between said stop-engaging members, said fillers being formed of sections, the top and bottom edges of one section being folded over the other whereby they are adjustably connected, the outer ends of said sections having flanges thereon, the flange of one section having key-hole slots 5 therein to engage screws on the end of the casing, and the flange of the other being adapted to engage the stops of a window.
4. The combination with a casing adapted to rest on a window-sill, of window stop-engaging members having longitudinal slots 10 therein, the upper members being adapted to telescope into said casing and the lower members being arranged on the front side of said casing at the bottom thereof; bolts 15 for securing said upper stop-engaging members in position, arranged through the said slots thereof, said bolts being provided with nuts on the inside of said casing; screws for securing said lower stop-engaging members 20 in position, arranged through the said slots thereof; and a door for the front of said casing, said door being hinged at its upper edge.
5. The combination with a casing adapted to rest on a window-sill, of window stop-engaging members having longitudinal slots 25 therein, said members being adapted to telescope into said casing; bolts for securing said stop-engaging members in position, arranged through the said slots thereof, said bolts being provided with nuts on the inside 30 of said casing; adjustable fillers arranged at the ends of said casing; a partition for said casing arranged transversely thereof; 35 a door for the front of said casing; and an outer door for said casing opening into one of the compartments thereof.
6. The combination with a casing adapted to rest on a window-sill, of window stop-engaging members having longitudinal slots 40 therein, said members being adapted to telescope into said casing; bolts for securing said stop-engaging members in position, arranged through the said slots thereof, said 45 bolts being provided with nuts on the inside of said casing; adjustable fillers arranged at the ends of said casing; and a door for the front of said casing.
7. The combination with a casing adapted to rest on a window-sill, of window stop-engaging members having longitudinal slots 50 therein, said members being adapted to telescope into said casing; bolts for securing said stop-engaging members in position, arranged through the said slots thereof, said 55 bolts being provided with nuts on the inside of said casing; a partition for said casing arranged transversely thereof; a door for the front of said casing; and an outer door for said casing opening into one of the compartments thereof.
8. The combination with a casing adapted to rest on a window-sill, of window stop-engaging members having longitudinal slots 60 therein, said members being adapted to telescope into said casing; bolts for securing said stop-engaging members in position, arranged through the said slots thereof, said bolts being provided with nuts on the inside of said casing; and a door for the front of said casing.
9. The combination with a casing adapted to rest on a window sill, of adjustable window stop-engaging members adapted to telescope into said casing; and means for securing said stop-engaging members in position adapted to be manipulated only from the inside of the window.
10. The combination with a casing adapted to rest on a window-sill, of adjustable window stop-engaging members; fillers arranged at the ends of said casing, said fillers being formed of telescoping sections; a partition for said casing arranged transversely thereof; a door for the front of said casing; and an outer door for said casing opening into one of the compartments thereof.
11. In a structure of the class described, a casing comprising bottom, side walls and a top, said top being inclined and consisting of an inner wall and an outer wall, said outer wall being formed of sheet metal and having downturned flanges at its edges and being adapted to embrace the edges of the inner wall, said walls being spaced to form an air chamber between the same, there being ventilating openings at the upper and lower edges of said chamber and through said casing bottom and said inner top wall.
12. In a structure of the class described, a casing comprising bottom, side walls and a top, said top being inclined and consisting of an inner wall and an outer wall, said walls being spaced to form an air chamber between the same, there being ventilating openings at the upper and lower edges of said chamber and through said casing bottom and said inner wall.
13. The combination with a casing adapted to rest on a window-sill, of adjustable window stop-engaging members having brads in the ends thereof, said casing being provided with brads adapted to engage said sill; and fillers arranged at the ends of said casing.

In witness whereof, I have hereunto set my hand and seal in the presence of two witnesses.
